UNITED STATES PATENT OFFICE.

ALBERT T. KELLER, OF PITTSBURG, PENNSYLVANIA.

ROLLING-MILL.

No. 873,439.

Specification of Letters Patent.

Patented Dec. 10, 1907.

Application filed May 11, 1905. Serial No. 259,876.

To all whom it may concern:

Be it known that I, ALBERT T. KELLER, a citizen of the United States, residing at Pittsburg, in the county of Allegheny and State of Pennsylvania, have invented certain new and useful Improvements in Rolling-Mills, of which the following is a specification, reference being had therein to the accompanying drawings.

10 One object of this invention is to so support the adjustable roll and driving spindle coupled thereto that each of the roll bearings and adjusting screws is subjected to the same amount of pressure, thus avoiding 15 unequal wear. The gage of the roll-pass is thereby preserved, resulting in the production of plates of uniform thickness. Very slight variation in the thickness of boiler and other plates, skelp, etc., is objectionable, 20 usually resulting in their rejection, hence the necessity for extreme accuracy. With the rolls supported as heretofore, constant watching and frequent adjustment and renewal of the bearings is necessary owing to unequal 25 wearing of the latter.

A further object is to provide improved means for connecting the roll-supporting means with the bearings.

Another object is to provide a roll-supporting mechanism which may be utilized as 30 an elevator for raising and lowering the rolls in the housings when inserting and removing them.

An embodiment of the invention is illustrated in the accompanying drawings applied to a two-high mill, Figure 1 being a side elevation, partly broken away and partly in section, of such a mill equipped with the improvements. Fig. 2 is a vertical 40 cross-sectional view of one of the housings and roll bearings thereof, the plane of section being indicated on Fig. 1 by the line 2—2, and Fig. 3 is a similar view taken on line 3—3 of the same figure. Fig. 4 is a sectional detail view taken on line 4—4 of Fig. 1. Fig. 5 is a detail view of one of the suspending bars. Fig. 6 is a side elevation illustrating the improved mechanism in use for changing the rolls.

50 Referring to the drawings, 2 designates the roll-housings which may be of the usual or any preferred construction, and 3 is the bridge or upper structure between and connecting the upper portions of the housings. 55 4 is the lower roll and 5 the upper roll, bearings 6 of the latter engaging adjusting

screws 7 which are raised and lowered by worm-wheels 8 driven by worm-shaft 9 which may extend from an electric motor 10. No novelty is claimed for the screw 60 adjusting mechanism, which may be arranged as here shown or in any other preferred manner.

Mounted on bridge 3 is cylinder 11 of a hydraulic lift or ram, and carried by plunger 12 thereof is cross-head 13 from which depend hangers 14, the hangers being held in perpendicular position by guide-lugs 3'. Preferably pivoted at 14' to hangers 14 is the roll-support which may consist of two 70 horizontal parallel bars 15, extending longitudinally of the mill through the housing-windows, and suspended from this support are bottom bearings 16 of the upper roll. While the connection between the support 75 and bearings may be made in any suitable manner, I prefer to employ rods 17, which extend vertically within the housings, being hooked at their upper ends to overhang the bars and extending through bearings 6 and 16, with keys 17' beneath the latter.

In Fig. 1 is illustrated a portion of the driving pinion mechanism 18 and housing 19 therefor, with driving spindle 20 extending to lower roll 4, and a similar spindle 21 for the upper roll, all being of usual and well known construction. Spindle 21 is adjustably supported by bearing 22 pivotally carried by the two longitudinal bars 23. These bars are sustained at one end by links 24 depending from pinion-housing 19, and at their opposite ends are connected by links 25 with the extremities of bars 15. Thus the supporting mechanism, which is common to the roll and the driving spindle, is separately 90 connected thereto, and with the roll relieved of the weight of the spindle the load on both bearings of the roll is the same, resulting in equal wear. The hydraulic lift is located at one side of the center of bridge 3 in order to 100 balance the load thereon and to equalize the pressures on the adjusting screws.

To facilitate the operation of inserting or changing rolls the improved mechanism may be utilized as an elevator, as indicated in Fig. 6. At such time the driving spindles are disconnected and the roll-wabblers are embraced by chains 26 depending from bars 15. To prevent bars 15 from tilting, lift connection 14' being at one side of the center, 110 the lower extremities of hangers 14 are formed with lateral extensions 27 which

form a passage for bolt 28 which is projected therethrough and through apertures 15' in bars 15, thus providing a rigid or non-tilting lifting mechanism. Guide-lugs 3' are of special service at this time as they prevent hangers 14 from oscillating. The rolls may thus be quickly and conveniently raised or lowered in the housing as may be required when inserting or removing them.

10. While I prefer to employ a single hydraulic lift mechanism having a pivoted connection with the roll and spindle support, the invention is not thus restricted.

I claim:

15. 1. In a rolling-mill, a roll, a driving spindle, and supporting mechanism with which the roll and spindle have separate and distinct sustaining connections.

2. In a rolling-mill, a roll and its bearings, adjusting means, a driving spindle, and movable supporting means with which the roll bearings and spindle have separate and distinct connections.

25. 3. In a rolling-mill, a roll and its bearings, a driving spindle, a supporting member with which the roll bearings and spindle have separate and distinct connections, and lift mechanism connected to said member.

30. 4. In a rolling-mill, a roll and its bearings, adjusting screws engaged by the bearings, a vertically movable supporting member extending longitudinally of the roll, roll-sustaining connections between said member and the roll bearings, and a driving spindle 35 having a sustaining connection with said supporting member.

5. In a rolling-mill, a roll and its bearings, a driving spindle, and lift mechanism connected to the roll bearings and having a 40 separate and distinct connection with the spindle.

45. 6. In a rolling-mill, a roll, a spindle, a supporting member separately connected to the roll and spindle, and lift mechanism having a pivoted connection with the supporting member.

50. 7. In a rolling-mill, a roll and its bearings, a driving spindle, a supporting member connected to the roll bearings and separately connected to the driving spindle, and a single hydraulic lift having its plunger pivotally connected to the supporting member.

8. In a rolling-mill, the combination of rolls and bearings therefor, roll-lifting means, means for connecting the bearings of the upper roll to the lifting means, and means for directly connecting the rolls to said lifting means for raising and lowering them in the housings. 55

9. In a rolling-mill, the combination of rolls and bearings therefor, a support, means for connecting the bearings of the upper roll to the support, means for connecting the rolls directly to the support, and a single lift mechanism for raising and lowering the support. 60 65

10. In a rolling-mill, the combination of housings, rolls, a support above and extending longitudinally of the rolls and through the housings, detachable connections between the upper roll-bearings and said support, means for detachably connecting the ends of a roll to said support, and support-lifting means. 70

11. In a rolling-mill, the combination of rolls, driving spindles, a support adapted interchangeably to sustain either a roll alone or a roll and its spindle, lifting means having pivotal connection with the support, and means for making rigid said pivotal connection. 75 80

12. In a rolling-mill, the combination of rolls, a support above and extending longitudinally of the rolls, a single lift above the support, hangers depending from the lift and pivotally connected to the support, means for making rigid said pivotal connection, means for connecting the opposite ends of the roll to said support, a roll-driving spindle, a spindle support, and a connection between the spindle-support and said longitudinal support. 85 90

13. In a rolling-mill, housings, rolls, a support extending longitudinally of the rolls and through the housings, lift mechanism for raising and lowering the support, and means for connecting the wabblers of a roll to said support. 95

In testimony whereof I affix my signature in presence of two witnesses.

ALBERT T. KELLER.
